UNITED STATES PATENT OFFICE.

JESSE CRITZ KING, OF ST. CATHARINES, ONTARIO, CANADA, ASSIGNOR TO WILLSON CARBIDE COMPANY, LIMITED, OF ST. CATHARINES, ONTARIO, CANADA, A CORPORATION OF ONTARIO.

ACETYLENE-GENERATOR.

No. 861,734.

Specification of Letters Patent.

Patented July 30, 1907.

Application filed March 31, 1905. Serial No. 253,000.

To all whom it may concern:

Be it known that I, JESSE CRITZ KING, a citizen of the United States, residing in St. Catharines, in the Province of Ontario, Dominion of Canada, have invented certain new and useful Improvements in Acetylene-Generators, of which the following is a specification.

This invention relates to apparatus for generating acetylene gas, and aims to provide certain improvements therein.

The invention is especially directed to a device for utilizing granulated or powdered calcium carbide in the manufacture of acetylene gas, although it is susceptible of use for other purposes. Prior attempts to utilize carbide of calcium in a finely subdivided form have not been successful, due principally to the tendency of the fine carbide when fed to the generating chamber to remain temporarily upon the surface of the water, forming floating masses or "islands". When such an island of fine carbide is finally submerged, the evolution of gas takes place very quickly, with the result in many cases that the escape pipe is not able at once to carry off the gas from the generator. Many serious explosions have resulted from this cause. According to my invention, I provide a generator having a means for preventing the formation of such floating masses of carbide, which preferably acts to maintain the water in constant circulation, so that the upper part of the water into which the carbide is fed is continuously replaced by a fresh supply from beneath, so that the water is maintained in a cool condition, and the gas is delivered out of the apparatus at a much lower temperature than heretofore. My invention includes certain other features of improvement, which will be hereinafter more fully described.

Referring to the accompanying drawings, which illustrate one form of my invention,—Figure 1 is a front elevation, partly in section, of a generator adapted for manual operation; Fig. 2 is a side elevation; Fig. 3 is a plan; Fig. 4 is a vertical section taken approximately on the line 4—4 in Fig. 3.

Referring to the drawings, A is a chamber which is designed to contain calcium carbide, or other gas-forming material, in a finely divided condition, such chamber being provided with a gas tight door or cover a, and having at its lower end a hopper b, the lower part of which leads to the feeding device B. The latter is designed to feed the carbide slowly, and in small quantities, to the generating chamber C, which contains a suitable supply of water, which, reacting with the carbide evolves acetylene gas in the well-known manner. The feeding device B, as shown, comprises a screw conveyer, the screw c of which is mounted to turn in a bearing d, on the front of the device, a sprocket

wheel e being provided for rotating the screw, and 55 being in turn rotated by a sprocket f, to which it is connected by a chain belt g, as best seen in Fig. 2. Considerable difficulty has been heretofore met in the operation of such feeding means, due to the fact that dust or lime from the carbide often formed at the 60 mouth of the conveyer, resulting in the clogging of the latter, so that it was unable to feed properly.

According to my present invention, I provide means for cleaning the feed opening whenever necessary, so that the action of the device is rendered more reliable. 65

As shown, this device consists of an angular blade or scraper h (Fig. 4), which is fixed at the lower end of a shaft i, mounted immediately above the feed opening of the conveyer, screw c, said scraper extending past the end of the screw into the generating chamber. 70 The shaft i is provided at its upper end with a hand wheel j, by which the scraper or blade h can be moved around the feed opening, thus effectually loosening any deposit at this point, and permitting the free action of the conveyer screw c. 75

The carbide, as it is fed by the conveyer, drops into the generating chamber C, and by reason of its finely divided condition tends to float upon the surface of the water contained in the latter until it is sufficiently wet to submerge. As before stated, there is also a 80 tendency for it to form itself into floating masses or "islands", which, when they finally sink beneath the surface of the water, are quickly acted upon by the latter because of their fine condition, with the result that a sudden and excessive evolution of gas takes 85 place, and in many instances a dangerously high pressure is generated. According to my invention, I aim to avoid this disadvantage, and to this end I provide a means for preventing the formation of such islands, and causing the carbide as soon as it falls from the feeding device to be submerged, whereby the generation of gas proceeds evenly without substantial variations in pressure. The means which I prefer to employ for this purpose is an agitator or paddle wheel D, which is mounted within the chamber C, its shaft extending 90 outwardly to the front of the device, and being there provided with a crank handle k or other means for rotating it. The effect of the paddle wheel is to submerge the particles of carbide immediately after they reach the surface of the water, thus preventing the 100 formation of aggregations of carbide, and to maintain the water in a constant circulation, and, to some extent, in a condition of agitation. Should any "islands" be partially formed, they will be immediately broken up by the action of the paddle wheel or by the movement of the water, so that all danger of the submersion of a considerable quantity of carbide at one time is avoided. In generators of this type, as heretofore

made, the upper portion of the water, being that which is chiefly exposed to the reaction, speedily becomes heated, with the result that the gas which is drawn from the apparatus is of a high temperature. In many instances, the heat evolved is sufficient after a short working to polymerize the gas. By producing a constant circulation of water within the generating chamber the entire body of water is maintained at substantially the same temperature; and, as the heat is diffused throughout the whole body, a much greater quantity is given off by the walls of the generator than is the case when the heat is localized in the upper part of the chamber.

E is the usual water seal chamber open at its top, and connected with the generator C at its lower part, a partition I separating the two at their upper parts, as best seen in Fig. 4. The gas is led from the generating chamber C by a pipe m at the upper part of the chamber, which may lead directly to the service pipe or 20 gasometer, but, according to my invention, I prefer to pass the gas through a scrubbing device before leading it to the point of use.

The form of scrubbing device which I prefer to employ is that shown at F, Fig. 4. This, in its preferred form, consists of a chamber or receptacle, into which the gas is led through a pipe n, connected to the pipe m by a tee-fitting o. The lower end of the pipe n is continued downwardly to a point near the bottom of the scrubber, and is there provided with a deflector p which distributes the gas throughout the water in the scrubber, the gas passing upwardly until it meets a perforated diaphragm q which more finely divides it, so that it is thoroughly commingled with the water, and deposits any fine dust or other matters which it 30 may carry, the latter settling in the bottom of the scrubber in the form of a sediment. The purified and further cooled gas passes out through the pipe r to the service pipe or gasometer. The scrubber is supplied with water in any suitable manner. In the construction shown, the tee-fitting o is provided at its upper end with a screw plug s, which is designed to be removed so that the supply of water may be introduced into the device through the pipe n. A suitable gage may be used to determine the height of the water, or a pet 40 cock t may be employed, as shown in Fig. 2, which is left open during filling until the water overflows through the cock, when the supply is cut off. A similar cock u is provided at the bottom of the scrubber, by means of which the used water may be drawn out of the device. 50 The scrubber is preferably provided with a door v, as shown in Fig. 2, by means of which the interior of the device is rendered accessible.

The generator is preferably provided with a valved outlet w at its side, through which the sludge may be 55 drawn out of the apparatus, and is also preferably provided with a bottom valve w' for a like purpose. To render the interior of the generator accessible for cleaning out the refuse, or for other purposes, it is provided near its bottom with an enlarged opening, which is closed 60 by a suitable door b', as best seen in Fig. 2. To facilitate the removal of the sludge from the apparatus, I preferably provide a stirring paddle v' at the bottom of the apparatus, which is mounted at the lower end of a shaft u', the latter being turned by a hand wheel e' at 65 the top of the device.

In operation, the chamber A is filled with carbid, and water is introduced into the chamber E until it reaches the level x--e in chambers E and C. The scrubber is filled to the level y--y (Fig. 4), and the crank handle z is turned to rotate the screw e of the 70 feeder B. The carbid is thereby fed into the generating chamber C in small quantities, falling upon the surface of the water and being immediately submerged by the action of the paddle wheel D. The pressure caused by the evolution of the gas will depress the level 75 of the water in chamber C slightly below that in chamber E. As the carbid is in subdivided form, the reaction necessary to evolve the gas takes place principally immediately after the carbid is submerged, so that the upper portion of the water in the chamber C tends to 80 become quite hot, but by the action of the paddle wheel D, the heat is distributed substantially throughout the entire body of water, and a considerable portion is conducted away by the walls of the generator. The comparatively cool gas, then passing through the scrubber, is purified, and passes off to the service pipe or 85 gasometer.

I have found in practice that the generator herein described not only makes practicable the use of finely divided carbid, but delivers the gas in a much better 90 condition than those generators which are designed for use with carbid in large pieces or lumps. The gas reaches the burners in a practically pure state, produces the maximum light efficiency, and causes much less trouble by reason of carbonization at the burner 95 tips than with previous generators. In operation, the evolution of gas proceeds without substantial variations in pressure, so that all danger of explosion is avoided.

It will be understood that I do not wish to be limited to the details of construction shown, as many changes 100 can be made therein without departing from the invention. Other devices may be substituted, for instance, for the paddle wheel illustrated, and such devices, as well as the feeding mechanism may be driven from any suitable source of power instead of by hand, as shown. 105 The operation of the device may, if desired, be controlled by any suitable governor actuated by increase of pressure in the gasometer or otherwise. These and other changes may be made while still retaining some or all of the advantages of my invention.

I claim as my invention the following defined novel features substantially hereinbefore specified, namely:

1. In apparatus for generating acetylene gas from finely divided carbid, the combination of a generating chamber adapted to contain water, means for feeding the carbid on to the surface of the water, an agitator adapted to permit the carbid to be fed onto the surface of the water, and means for causing said agitator to act to produce a rapid agitation of the water during normal feeding of the carbid, whereby the fine particles of the carbid are submerged substantially as fast as they are fed.

2. In apparatus for generating acetylene gas from finely divided carbid, the combination of a generating chamber adapted to contain water, means for feeding the carbid on to the surface of the water, a paddle wheel mounted in said chamber and adapted to permit the carbid to be fed onto the surface of the water, and means for imparting a rotative movement to such paddle wheel to produce a rapid agitation of the water during normal feeding of the carbid, whereby the fine particles of the carbid are submerged substantially as fast as they are fed.

3. In apparatus for generating acetylene gas from finely divided carbid, the combination of a generating chamber adapted to contain water, means for producing a normal

feeding of carbid on to the surface of the water, a paddle wheel mounted in said chamber, being adapted to permit the carbid to be fed onto the surface of the water, and such paddle wheel being connected to such feeding means, 5 and means for operating said wheel and means, so that the wheel produces a rapid agitation of the water during the normal operation of such feeding means, whereby the fine particles of the carbid are submerged substantially as fast as they are fed.

10 4. In an apparatus for generating acetylene gas or the

like, a generating chamber, a feeding device for the carbid having a screw *c* and a scraper *h* extending past the end of said screw into said chamber, for maintaining a free passage from said device to said chamber.

In witness whereof, I have hereunto signed my name in 15 the presence of two subscribing witnesses.

JESSE CRITZ KING.
